ROSARY

Robert J. Reilly, North Attleboro, Mass., assignor to
Evans Case Co., a corporation of Massachusetts

Application December 2, 1953, Serial No. 27,870

Term of patent 14 years

(Cl. D45—16)

FIG. 1

To all whom it may concern:

Be it known, that I, Robert J. Reilly, a citizen of the United States of America, residing in North Attleboro, county of Bristol, State of Massachusetts, have invented a new, original, and ornamental Design for a Rosary, of which the following is a specification, reference being had to the accompanying drawing, forming a part hereof.

Fig. 1 is a front elevational view of a rosary showing my new design;

Fig. 2 is an enlarged fragmentary view thereof taken between the lines 2—2 of Fig. 1; and

Fig. 3 is a side elevational view of the fragment of Fig. 2.

I claim:

The ornamental design for a rosary, substantially as shown.
